United States Patent Office.

ALEXANDER J. FORBES, OF SAN FRANCISCO, CALIFORNIA.

Letters Patent No. 96,788, dated November 16, 1869.

IMPROVED CABINET FOR LADIES.

The Schedule referred to in these Letters Patent and making part of the same.

To all whom it may concern:

Be it known that I, ALEXANDER J. FORBES, of the city and county of San Francisco, State of California, have invented a certain new and useful "Cabinet for Ladies;" and I do hereby declare that the following is a full, clear, and exact description of the same, reference being had to the accompanying drawings, and letters marked thereon.

My invention relates to the combination and arrangement of a sewing and toilet-table and receptacle, writing-desk, fire-screen, arbor for running plants and trailing vines, stand for fish-globes or statuary, and card-holder.

In the drawings—

Figure 1 represents a front elevation of my cabinet.

Figures 2, 3, 4, 5, 6, and 7, are details of hinges and screws for hanging and adjusting the position of the centre-glass.

Figures 8 and 9, a plan and section of concave drawers or needle-holders.

Figure 10, an elevation of work-table and sewing-bag.

Figures 11 and 12 show details of construction of pen-receptacle, and forming part of the secretary.

To enable others skilled in the art or science to which it most nearly appertains, to make and use my invention, I will proceed to fully describe its construction and operation.

In constructing my cabinet, the front portion of the top is cut out to admit the secretary, which consists of receptacles, *a b c*, for paper, ink, and wafers; also, a pen-receptacle, which is provided with a concave cover, *d*, which rests on supports *e*, with rounded ends, so that by pressing down on the cover, one end of it will be raised for easy access, shown at figs. 11 and 12, sheet 2. When not in use, a lid folds over the face of the desk.

At each side, and immediately below the secretary, are narrow drawers, *f f*, with concave bottom, for crotchet and knitting-needles.

These drawers, when extended, also act as supports for the desk-lid, when thrown back. Shown at figs. 8 and 9, sheet 2.

A table, *g*, is placed under the desk, with an opening in the top, which is provided with a work-basket or bag, *h*, which slides in and out of the cabinet on ways, so that when in haste, the lady may throw the

work that she is engaged on quickly down, and remove it out of sight by pushing back the table.

The front of the table may be carved to suit the fancy.

The remaining space of the front of the cabinet is filled with drawers, *i i i*.

At both sides of the cabinet, I place double fire-screens *k k*, for drying laces, and other purposes, and which, when not in use, fold up in the cabinet, and are flush with the surface. Shown at fig. 1.

In ledges in the back part of the cabinet, at each side, are placed pots *l l*, in which may be placed earth for flowering plants or vines, to run over the arbor or carved frame *m*, and on the top, in the centre of the arbor, is a pot or basket, for hanging wall-flowers, and beneath which may depend the bird-cage *n*.

The rounds of the arbor pass into a frame at the back of the cabinet, in which are placed three mirrors. The centre one, being the larger, is pivoted to the frame by hinges *o o*.

For changing the position of the centre-glass, a thumb-screw, *p*, is employed, which operates in a lug, *p'*, attached to the frame of the glass, and, by turning the screw, the desired angle of inclination is obtained without the necessity of raising out of the seat by the operator.

Stands, *r r*, are stationed at each side of the cabinet, under the bower, upon which may be placed fish-globes or statuary, and beneath is a basket for visiting-cards.

Thus, an elegant and handy piece of furniture is provided, which will impart cheerfulness to the room in which it is placed, and be very useful and convenient to the ladies of a household.

Having thus described my invention,

What I claim, and desire to secure by Letters Patent, is—

The combination and arrangement of the cabinet, as described, consisting of the desk *a b c*, narrow drawers *f f*, work-table *g*, basket or bag *h*, and fire-screens *k k*, in the manner described, for the purpose set forth.

In witness whereof, I have hereunto set my hand and seal.

A. J. FORBES. [L. S.]
